Sam'l F. Hodge

UNITED STATES PATENT OFFICE.

SAMUEL F. HODGE, OF DETROIT, MICHIGAN.

STAMPING-MILL FOR CRUSHING QUARTZ.

Specification of Letters Patent No. 30,821, dated December 4, 1860.

To all whom it may concern:

Be it known that I, SAMUEL F. HODGE, of Detroit, in the county of Wayne and State of Michigan, have invented certain new and 5 useful Improvements in Ore Crushing or Stamping Mills; and I do hereby declare that the following is a full, clear, and exact description of the same, reference being had to the annexed drawings, making a part of 10 this specification, in which—

Figure 1, is a side elevation of my invention; Fig. 2, an end elevation of the same; Fig. 3, a plan or top view of the same; Fig. 4, a horizontal section of the mortar of the 15 same, taken in the line C, D, Fig. 5. Fig. 5, a vertical section of the mortar taken in the line A, B, Fig. 2. Fig. 6, a detached side view of the lifting device.

Similar letters of reference indicate corresponding parts in the several figures.

This invention relates to a novel and improved means employed for elevating the plunger or pestle and liberating the same at the desired point, substantially as herein- 25 after fully shown and described, whereby a rising and falling movement is given the plunger or pestle with a moderate application of power, and without any undue friction and consequent wear and tear of the 30 working parts.

To enable those skilled in the art to fully understand and construct my invention I will proceed to describe it.

A, A, are two uprights, which are connected at their upper ends, by a cross bar B, and connected at about their centers by a cross bar C. These cross bars B, C, form guides for a plunger or pestle rod D, which has a wedge or V-shaped frame E, secured 35 to its upper part. This wedge or V-shaped frame E, is shown clearly in Figs. 1, and 6. By referring to these figures it will be seen, that its point or smaller end, is downward and that it is placed centrally on the rod D.

40 The uprights A, A, are each provided with two horizontal arms E, E, projecting from opposite sides, in the same horizontal plane. On these arms are the bearings a, of shafts F, F. These shafts are parallel 45 with each other and are connected at one end by toothed wheels G, G.

On each shaft F, there is placed an eccentric or cam H. The eccentricity of the

55 cams H, that is to say, their departure from circles correspond precisely with the taper or obliquity of the wedge or V-shaped frame E, so that as the cams H, H, rotate, their peripheries will at all points of their rotation be in contact with the sides of the wedge or V-shaped frame E, the increasing 60 radii of the cams corresponding with the diminishing width of the wedge or V-shaped frame E. By this arrangement it will be seen that by rotating one of the shafts F, a reciprocating or rising and falling movement will be given the rod D, the cams H, H, elevating the rod in consequence of acting against the wedge or frame E, and the rod falling by virtue of its own gravity when the prominences of the cams have 70 passed the sides of the wedge or frame E. The latter being provided with projections b, for the cams to catch against and commence their action on the wedge or frame, 75 see Fig. 6.

The pestle I, which is at the lower end of the rod D, works in a mortar J, of quadrilateral form. This mortar has inserted in each side of it an inclined screen K. These screens are formed of parallel rods c, placed 80 in proper frames or in the sides of the mortar and inclined at an angle of about $22\frac{1}{2}$ °, see Fig. 5.

The "pulp" or pulverized rock is forced 85 through the screens K, by the action of the pestle I, and a stream of water which is admitted into the top of the mortar. The pestle I, performs therefore a double function; to wit, the crushing or breaking of 90 the ore and the forcing of it through the screens.

I am aware that stampers have previously been operated by cams and tappets of various forms in connection with collars or arms upon the stamper shafts and also that rollers whose peripheries are not complete circles have been used to elevate straight stamper shafts by friction.

The peculiar construction and combination of parts which I have above described 100 present the following practical advantages: Friction is not depended upon to elevate the stamper shaft. The first impact between the segments H, and the stamper shaft is at a point in the former which is 105 moving slowly and by reason of the wedge

or V form of the frame and the eccentricity of the segments the shaft is elevated securely and effectually and with increasing velocity until released.

5 I claim as new and of my invention herein and desire to secure by Letters Patent—

The combination of the eccentric cams H, H, wedge or V shaped frame E, and

stamper shaft D, the whole being constructed substantially as and for the purposes set forth.

SAML. F. HODGE.
